INVENTOR.

Morris S. Rankin,

BY

J. Stuart Freeman,
ATTORNEY.

UNITED STATES PATENT OFFICE.

MORRIS S. RANKIN, OF MOUNT EPHRAIM, NEW JERSEY.

SOUND REPRODUCER.

Application filed May 12, 1921. Serial No. 468,889.

To all whom it may concern:

Be it known that I, MORRIS S. RANKIN, a citizen of the United States, residing at Mount Ephraim, in the county of Camden and State of New Jersey, have invented certain new and useful Improvements in Sound Reproducers, of which the following is a specification.

The object of this invention is to provide an improved sound reproducer for talking-machines and the like, which in its preferred form can be manufactured at a low cost, and is particularly adapted for use as a part of toy devices of this character.

Another object is to provide an improved mounting for the stylus bar, whereby the same is separated from the sound box casing by a non-conducting or sound insulating member, thus preventing the objectionable "scratch" of the needle in the groove of the record from being conveyed to the said casing, as by a continuous metallic path.

A further object is to provide in such a device a diaphragm-retaining gasket having an axially directed extension operative to form the yielding, resilient, sound-insulating support for the stylus bar.

And still another object of the invention is to provide an improved method of mounting the diaphragm within the sound box casing; to provide an improved means for holding the stylus in co-operation with the stylus bar of the reproducer; to provide an improved method of attaching one end of the said stylus bar to the diaphragm; to provide an improved manner of supporting said reproducer, and other details of construction and operation fully brought out in the following description, when read in conjunction with the accompanying drawings

in which Fig. 1 is a side elevation of the reproducer and the adjacent end portion of an amplifier; Fig. 2 is an enlarged diametrical section of the sound reproducer in its preferred form; Fig. 3 is a transverse section of the same; Fig. 4 is a plan view of the diaphragm free of the reproducer; and Fig. 5 is an enlarged detail perspective view of the folded metal blank from which the stylus bar is formed.

Referring to the drawing, it will be noted that the invention relates to the sound-reproducers for talking-machines, no other part of the same being illustrated except the small end of a tapering amplifier 1 and a

line 2 which represents the plane of any well-known form of disc record.

The reproducer per se comprises an annular metallic member 3 preferably having a plane face 4, while its rear portion is provided with a laterally extending integral projection 5 having an aperture 6 which forms the exit end of a channel tapering towards the inlet 27, which same is preferably positioned centrally of the plane face 65 of said member, and it is into the enlarged channel end 6 that the reduced end portion 8 of the amplifier 1 is firmly positioned.

An annular disc gasket 9 is provided, the same being positioned in uniform contact 70 with the outer marginal edge portion of the face 4 of the member 3, and against which gasket is positioned the peripheral portion of a vibratory diaphragm 10, which diaphragm and gasket are both prevented from 75 movement with respect to the member 3 by means of a substantially cylindrical sheet metallic member 11, having a radially inwardly directed portion 12 closely surrounding the rear surface of the said member, 80 while its oppositely positioned marginal edge portion 13 is flared inwardly and forms a partial inclosure, within which there is positioned a substantially cylindrical gasket 14, bearing at its inner edge directly against 85 the outer surface of the said diaphragm adjacent to the periphery of the latter, while the union between said gaskets and diaphragm may be completely air-tight by means of a thin layer 15 of suitable cement, 90 which as shown in Fig. 4 preferably covers the exposed surfaces of the gasket 14 and encroaches well upon the radially outer portion of the exposed surface of said diaphragm.

The said gasket 14 is provided at one point with an extension 16, against the outer surface of which is closely positioned the correspondingly curved arms 17 of a stylus-bar 18, while the oppositely positioned extremities 19 of said arms surround and firmly grip the opposite limiting edges of the gasket projection 16, so that said projection forms a support for the stylus-bar, and also due to the material of which said support is formed it serves as a sound-insulating medium, operative to prevent the vibrations of the stylus-bar from being communicated to the other metallic parts of the reproducer as a whole.

Said stylus-bar comprises a shank portion formed of two thicknesses of metal folded together, the same being provided at their common adjacent end portions with lateral extensions 20, which are reversely bent and project transversely beyond the shank of said bar to form spaced fingers 21, which as clearly shown in Fig. 2 are adapted to extend through spaced apertures 22 in the said diaphragm, after which said fingers are folded to firmly grip the central apertured portion of the diaphragm in order to insure the latter vibrating in perfect harmony with the said stylus-bar.

15 The stylus-bar supporting arm 17 when being formed actually comprises bifurcated extensions of the folded side portions of the shank 18, while each of said arms has punched radially from its central portion 20 an ear 23, the same being provided with aligned apertures 24 and being normally in parallel relationship. As shown in the drawing, a pin 25 extends through the said apertures 24 and pivotally supports a cam 25 member 26 provided with a small thumb-operated lever 27, so constructed and particularly shown in Fig. 3 that a stylus-needle 28 may be inserted between the ears 23 of the stylus-bar and clamped in position by a partial rotation of the said lever, from which said needle may be readily removed as become worn by merely shifting the said lever in the opposite direction, after which as previously described a new needle 35 may be inserted in place of the former.

As the reproducer herein described is particularly adapted for use upon inexpensive and toy sound-reproducing machines, the member 3 may well comprise a metal casting, while the cylindrical member 12 may equally well be formed of a drawn tin punching, the diaphragm formed of thin

sheet metal, water-proofed paper product, bakelite, or the like, and the gaskets 9 and 14 of paper or the equivalent which has 45 preferably been previously water-proofed.

Having thus described my invention, what I claim and desire to protect by Letters Patent of the United States is:

1. A sound-reproducer, comprising a 50 stylus-bar formed of sheet-metal folded to provide a shank portion comprising a double thickness, the sides of said shank portion adjacent at one end being provided with oppositely extending fingers adapted 55 to be secured to a vibratory diaphragm, while the opposite end portions of said shank thicknesses are extended laterally in opposite directions to provide a support for said stylus-bar, and said arms being provided with integral parallel extending ears adapted to receive between them a removable stylus, and means pivotally carried by and between said ears operative to removably retain said stylus in position. 60

2. A sound-reproducer, comprising a 65 diaphragm, an annular supporting gasket therefor, and a stylus connected to said diaphragm and supported directly by said gasket. 70

3. A sound-reproducer, comprising a 75 diaphragm, a supporting gasket therefor having a lateral extension, and a stylus-bar connected to said diaphragm and mounted directly upon said extension. 75

4. A sound-reproducer, comprising a diaphragm, an annular supporting gasket therefor having an integral resilient extension, and a stylus-bar connected to said diaphragm and yieldingly mounted directly 80 upon said extension.

In testimony whereof I have affixed my signature.

MORRIS S. RANKIN,
